CONTAINER

Fred G. Foss, Hillside, N. J., assignor to American
Can Company, New York, N. Y., a corporation
of New Jersey

Application November 30, 1937, Serial No. 177,354

2 Claims. (Cl. 221—62)

The present invention relates to containers or cans for packaging powdered or granular products and the like and has for an object the provision of an improved cover which when in place on the can prevents buckling of the can side walls and prevents sifting of the contents through the opening thereby produced when the can is grasped for dispensing its contents.

Cans having slip covers or the like and of the character ordinarily used for talcum powder, condiments, spices, etc., are frequently made rectangular in shape and thus include long flat side walls which due to excess tightness of cover fit sometimes are easily crushed in under a side pressure applied on the walls in handling the cans. Such cans are usually provided with a strengthening bead in the upper part of the body but even this bead at times does not prevent distortion of the can walls under pressure. Such distortion breaks the tight frictional fit of the cover upon the body and thus permits the can contents to escape.

The present invention contemplates the prevention of this result by the provision in the can cover of opposed indentations at the center of its long sides which are for the purpose of supporting the straight upper edges of the flat sides of the body so that they cannot buckle inwardly when a side pressure is applied thereto during handling of the can.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a container having a slip cover embodying the instant invention; and

Fig. 2 is an enlarged transverse section of the upper portion of the container and the cover, the view being taken substantially along a plane indicated by the lines 2—2 in Fig. 1.

As a preferred embodiment of the invention the drawing discloses a can having a rectangular body 11 formed with short flat end walls 12 and longer flat side walls 13. The lower end of the can is provided with a bottom 14 which is secured to the body in any suitable manner as by a seam 15.

At their upper ends the side walls 12, 13 of the body are formed as a straight marginal portion or friction rim 16 which terminates in an upper edge 17 which is slightly turned or flared inwardly. Just below this rim 16 the body

walls are strengthened by a struckout bead 18 which extends entirely around the can body.

The upper end of the can is provided with a slip cover 21 having a flat top wall 22 which merges into a peripheral bead 23. The bead 23 curves over the top of the terminal edge 17 of the upper portion of the body rim 16 forming a clearance channel 24 for this edge when the cover is on the can. The bead merges into a depending flange 25 which extends down adjacent the flat outside surfaces of the body rim 16 and in tight frictional engagement therewith.

The top of the cover is preferably provided with a group of sifter openings 26 which are used for dispensing the can contents when the can body is gripped on its flat side walls and turned into an inverted position. The sifter openings are preferably covered when not in use by a slide 27 which is retained on the cover by a plurality of lugs 28 struck up out of the cover top wall 22. 20

During dispensing of the can contents through the sifter openings 26 the can is most conveniently gripped on the long flat side walls 13 of the body. Therefore it is usually these walls which are distorted by the side pressure thereon. Such distortion of the walls would ordinarily result in an inward movement of the body rim 16 away from the cover flange 25 and its edge 17 would move into the clearance channel 24 of the bead 23 thus forming a space or opening at the cover flange which would permit the undesirable escape 30 of the can contents. 25

To prevent such distortion of the can side walls 13 when pressure is applied thereto the cover bead 23 at the center of each of its long sides is formed with an indentation 31. These two indentations provide a pair of protuberances 32 which extend adjacent the inside surface of the body rim 16, the terminal edge 17 of which engages the outer wall of each protuberance on 40 each side as shown in Fig. 2 and thereby confines the rim against inward movement in these places. The inwardly turned rim edge 17 permits easy insertion of the body friction wall 16 inside of the cover wall 25 and at the same time 45 locks the long side walls against distortion when a gripping pressure is applied thereto.

It is thought that the invention and many of its attendant advantages will be understood from 50 the foregoing description, and it will be apparent that various changes may be made in the form, construction and arrangement of the parts without departing from the spirit and scope of the invention or sacrificing all of its material ad- 55

vantages, the form hereinbefore described being merely a preferred embodiment thereof.

I claim:

1. A container for granular products and the like, comprising a body having a friction rim adjacent its mouth, a cover having a peripheral bead terminating in a depending flange adapted to frictionally fit over said friction rim when the cover is on the body, said cover bead having indented portions at oppositely spaced areas thereof to provide protuberances spaced inwardly from said friction rim and extending down adjacent the inside surface of the body friction rim confining the rim between them and the flange of the cover, said protuberances supporting the rim of the body against disengagement from said cover flange thereby maintaining the tightness of said joint and preventing the escape of the container contents therethrough when a gripping pressure is applied to the container body during handling.

2. A container for granular products and the like, comprising a body having end walls and flat side walls terminating in a friction rim adjacent its mouth, a cover having a peripheral bead terminating in a depending flange adapted to frictionally fit over said friction rim when the cover is on the body, and indentations located on said cover bead intermediate the length of the flat side walls of said body to provide protuberances spaced inwardly from said friction rim and extending down adjacent the inside surface of the body friction rim section of said flat side walls confining this section of the rim between them and the flange of the cover, said protuberances supporting the flat side walls of the body against disengagement from said cover flange thereby maintaining the tightness of said joint and preventing the escape of the container contents therethrough when a gripping pressure is applied to the container body during handling.
